UNITED STATES PATENT OFFICE.

JOSEPH S. WILLIAMS, OF RIVERTON, NEW JERSEY.

METHOD OF CONSTRUCTING SUBAQUEOUS TUNNELS.

1,072,068.

Specification of Letters Patent.

Patented Sept. 2, 1913.

Application filed December 7, 1906, Serial No. 346,775. Renewed January 25, 1913. Serial No. 744,090.

To all whom it may concern:

Be it known that I, JOSEPH S. WILLIAMS, a citizen of the United States, residing at Riverton, Burlington county, State of New Jersey, have invented a new and useful Method of Constructing Subaqueous Tunnels, of which the following is a specification.

In the methods heretofore employed in the construction of subaqueous tunnels there have been great uncertainty in the work to be done and many unforeseen delays in construction with much danger in carrying out of the work and great uncertainty as to stability, alinement and the maintenance of pressure resistance, which have caused uncertainty as to the safety and life of the tunnel construction. The liability of leakage, owing to the breaking down of the elements encompassing the tunnel way from the instability of the foundation thereof and of the tunnel way encompassing elements, entails great leakage under practised methods and renders it necessary in nearly every case, to keep in constant operation a pumping apparatus of large capacity for removing such water from the tunnels.

The object of my present invention is to devise novel methods and means by which subaqueous tunnels may be constructed with economy, rapidity and freedom of the risks attending the present methods and in such a manner as to establish in tunnels absolutely reliable standards of subaqueous pressure resistance, the tunnel being so constructed that on any transverse section line it will be provided with absolutely reliable standards of reinforced subaqueous pressure resistance and water proof construction, and predetermined standards of traffic load bridging and supporting capacities and features of safety and bed reinforcement per predetermined unit length and width of the construction in continuity throughout such construction. Such tunnel construction is formed by placing transportable water proof tunnel sections of construction in accurate alinement as to grade and otherwise on a novel construction of a foundation bed which is reinforced to such standards of resistance as may be determined on any section line of such bed or in continuity. After the tunnel sections of such construction have been

placed in position and connected with each other, they are ballasted into union with the foundation bed of construction thereunder.

To the above ends my novel method consists in establishing a survey and structural chart above the bed of the water way, such chart showing the longitudinal and sectional lines and also the lines in accordance with which the water way is to be accurately excavated, graded and ballasted. After the survey lines of the tunnel have been established the bed of the water way is equipped with a continuous line of sheet piling for a desired distance and with piers so constructed as to accurately aline the tunnel sections while they are being lowered into position, such piers being so located that the joints or unions of meeting tunnel sections will rest thereon.

It further consists of a novel method of constructing tunnels wherein the foundation bed of construction is first prepared by excavating the bed of the water way, ballasting such excavated bed to a desired grade, such bed being reinforced, if desired, with piles capped with concrete and with piers at predetermined intervals.

It further consists in a novel manner of constructing the tunnel sections and establishing them in place on the foundation bed of construction.

It further consists of a novel method of uniting the different tunnel sections with each other and a novel method of uniting the ends of the tunnel ways with docks provided with water proof chambers communicating with the subway and surface traffic lines.

It further consists of a novel method of constructing tunnels wherein the tunnel sections are ballasted into union with the resistance bed thereunder, and lap joint and side line resistances are provided so as to provide, during the process of construction, a continuous tunnel way with bulk heads in the ends of each transportable section so that entrance may be made in the air locked tunnel sections from the shore ends, after all shall be laid or into one or more sections by suitable air shafts extending therefrom to the working platform of the alining system as the structures are established, whereby the operators can ballast each air locked section,

if not otherwise ballasted, remove the bulk heads to form the union at the meeting ends of the tunnel sections, and unite the chords and bridging elements, whereby a continuity 5 of bridging chord and bridging and reinforcing elements are in continuity from one end of the tunnel line to the other.

It further consists of a novel method of building tunnels, wherein the tunnel way is 10 encompassed by a bridging or supporting frame of structural metal or other suitable material or a combination of such, preferably water proofed to an inoxidizable standard and embedded partly or entirely in a reinforcing material continuously throughout the subaqueous tunnel line. The ends of the tunnel line are in reinforced and water proof anchorage with the water line chambers or wharf structures and in reinforced and reinforcing ballasted union with my novel construction of resistance bed and also with sub-way shore lines, it being understood that the chords or other elements are provided with a heavily reinforced inner lining backed by 20 water proofing and faced and embedded thereby and reinforced by a lining of heat resisting material having metal reinforcements embedded therein, if desired.

My invention also consists in a novel 30 method of forming the foundation bed of construction, a novel method of constructing the tunnel sections, a novel method of establishing such sections in place on the foundation bed and forming a union between the 35 meeting ends of adjacent tunnel sections, a novel method of uniting the tunnel sections with the foundation bed of construction and a novel method of uniting the tunnel line with the shore connections and other novel 40 features of construction, as will hereinafter appear in the detailed description of one manner of carrying out my method.

In order to illustrate one manner in which my method may be advantageously carried 45 out I have shown in the accompanying drawings one form of a construction which will give in practice satisfactory and reliable results.

Figure 1 represents a plan view of an 50 actual survey showing the depth of the water and also an alinement system and equipments for the construction of subaqueous tunnels embodying my novel method. Fig. 2 represents a sectional elevation of a sub- 55 aqueous tunnel line, showing in addition the shore connections and other equipments by which the accurate alinement and stability of the structure are obtained. Fig. 3 represents a plan view, partly broken away, showing 60 one of the alining piers or reinforcements of the foundation bed. Fig. 4 represents a plan view, partly broken away, similar to Fig. 3, but showing in addition the reinforced, ballasted head of the grade line 65 pier. Fig. 5 represents in sectional eleva-

tion, a grade line pier with one transportable tunnel section placed in alinement thereon, and the other tunnel section in co-alinement and co-action with the alining resistances and ready to be lowered into position 70 on the foundation bed. Fig. 6 represents a sectional plan view of Fig. 5. Fig. 7 represents a side elevation, partly in section, of a dredged channel way, and showing different stages of the construction. Fig. 8 represents 75 a sectional perspective view of one of the piers showing more clearly the manner in which the union of the two sections is accomplished. Fig. 9 represents a sectional elevation of a portion of an inner lap joint 80 union, and also showing means for establishing a water seal across the meeting ends of the tunnel alined structures. Fig. 10 represents a plan view of Fig. 9. Fig. 11 represents a perspective view of a water bed, 85 showing different stages in the construction of a tunnel in accordance with my novel method. Fig. 12 represents a perspective view, partly in section, showing more clearly another step in the construction of tunnels 90 in accordance with my novel method.

Similar numerals of reference indicate corresponding parts in the figures.

Referring to the drawings:—in order that my novel method may be readily understood 95 I will, when possible, in the detailed description of such method, take up the different stages of construction in the natural or logical sequence in which they take place in the actual carrying out of the tunnel construction. 100

The working chart.—The first step in the construction of tunnels in accordance with my novel method, is to survey the tunnel line and provide a longitudinal tunnel line 105 1, see more particularly Figs. 1 to 3, the grade resistance line 2, see Figs. 4, 5, and 7, the exact alining lines 3—3 and the approximate lines 4—4. After such alining lines are established and indicated by suitable 110 means along the alined water bed, the transverse sectional lines 6 are defined, said lines indicating the transverse sectional center line of the piers 85, see Fig. 3. The sectional lines 9 and 10, Fig. 3, are located and 115 also such section lines 6 at which the meeting ends of tunnel sections are located as indicated at 19.

The foundation bed.—Side pilings or walls 5 are next established for a desired distance 120 equidistant from the center line 1 and substantially on the approximate alining lines 4—4, such side pilings being adapted to support the alining and working platforms 7, which latter are built across the alined water bed and serve as approximate alining elements for the holding and placement of transportable tunnel sections and as side resistances for the establishment of suitable chambers after the sections have 125 130

been lowered into place so that a suitable union of the adjoining sections may be formed at such points as hereinafter described. After the platforms 7 are established along the sectional lengths of the water bed the center, dimensions and approximate lines of the structures are defined thereon and also a construction water level line, tunnel section lines and the other sectional alining lines for the establishment of suitable piers, so that the tunnel sections on being lowered onto the foundation bed will be located in proper tunnel alinement. After the side alining pilings 5 have been placed in position, the space between such pilings is excavated by dredging or otherwise, to a suitable grade, as seen at 16, Figs. 5 and 7. The graded bed is then ballasted, if desired, to an alinable grade, as seen at 15, Figs. 5 and 7, between the piers 85, to be hereinafter described, or the bed between such piers may be reinforced by pilings before or after the transportable sections have been placed and such reinforced bed ballasted with suitable material as concrete or cement to an alinable resistance grade 15, Figs. 5 and 7, or such bed may be reinforced throughout by ballasting which may also be reinforced by reinforcing material embedded therein, whereby when the transportable tunnel structures 13 and 14 are lowered into position they can be ballasted into union with the graded and alined resistance bed to form a continuity of structure throughout the length of the tunnel line. The pilings or walls 5 may be established along sectional lengths as a portion of the tunnel is completed and the alinement of the transportable sections proceed continuously or for any given length of sections and these side pilings serve as reinforcements for the foundation bed below the grade of the graded and alined bed 15 and as side alining and supporting resistances for the tunnel sections. This ballasting may be carried out by ballasting from the alining and working platforms 7 above the water line or from floating vessels 93, see Fig. 7, equipped with suitable means for conducting the ballast to the foundation and bed of the water way, or the ballasting may be partly carried out through ballasting ports in the tunnel sections, as hereinafter more fully described.

The bed of the construction may be reinforced to such a standard of resistance that the bridging capacity taken on any section line will be sufficient to support the maximum traffic passing thereover, without taking into consideration the traffic supporting capacity of the tunnel sections.

The piers 85.—As will be more fully hereinafter explained, each tunnel section is so constructed that it will have the requisite strength and bridging capacity if it is only supported at each end so that if the entire

bed of construction should give way between each end, the tunnel section would still have adequate factors of safety to support the maximum traffic load passing over such section and in order that provision may be made for said supports at the end of each tunnel section and otherwise at predetermined points throughout the tunnel line at predetermined distances, I reinforce the bed of construction preferably by forming piers 85 of a novel construction. The bed of construction at such points is suitably piled and these piles are capped with concrete, cement or other suitable material and this capping material is reinforced by metal elements, 80 having any desired contour, embedded therein and arranged in any suitable manner, these metal elements being afterward embedded in concrete, cement or asphaltum and built up to the grade line 2 of the tunnel line. The upper portion of the foundation portion of the pier 85 is provided with the transversely extending channel 207, see Figs. 5, 7 and 11, which extends from one side of the pier to the other and communicates with the chambers formed in the sides of the piers 85. The inner face of the piers 85 is provided with alining standards, the upper portions of which are inclined or beveled as indicated at 18 so that the tunnel sections when lowered, will be accurately guided into position, see Figs. 5 and 7, the inner portion 17 of the lower surface of these guide standards being approximately of the same diameter as the exact measurement of one of the transportable tunnel sections. These guiding members 17 and 18 form a lap joint chamber 54, see Figs. 6, 7 and 11, communicating with the chamber 207 and these chambers are preferably reinforced by metal elements, such as the bars 209 located therein, it being understood that after the sections are located in place on the foundation bed this chamber 54 will be filled with a sealing material, such as concrete or cement. Adjusting standards 11—11 are provided, as best seen in Figs. 6 and 7, the purpose of which will hereinafter appear. The top of the pier 85 is preferably formed by a capping member 53, the upper surface of which is on the tunnel grade line 2, as seen in Fig. 12. The pilings which form the sides of the piers 85 and to which the approximate alining members 18 and exact alining members 17 are secured are extended upwardly in order to support the platforms 7 on which the working chart is indicated. At suitable points along the tunnel line in the bed of construction I provide drainage wells 21, see Fig. 2, by establishing water tight chambers in water tight union with the drainage passageways of the tunnel system so that any seepage or fluid which may be carried into the tunnel system may be removed therefrom when necessary. I preferably establish such

drainage chambers under the structure and cap the chambers with reinforcements so that such structure is adapted to operate as a reinforced resistance in the bed of construction.

- 5 It is desirable in certain cases to build the tunnel sections in water proof chambers located at the ends of the tunnel line, which afterward can be finished and converted into wharves or piers at which vessels can discharge their cargoes, the water proof chambers of such wharves being connected, if desired, with subway systems, while the upper or wharf line floor may be connected 10 with the street traffic systems. In such cases the pilings or walls are established at greater distances apart than when used along the sides of the alined water bed, for the purposes of alinement and construction. 15 With such pilings established at suitable distances apart so as to form water tight walls, the ends of such walls are closed and the area encompassed by such walls is excavated to a non-resistance tunnel grade line 20 and such bed is suitably reinforced by pilings capped with ballast and water proofed into union with the encompassing walls or otherwise, as may be found necessary for establishing a stable resistance bed, primarily for the construction of transportable 25 tunnel sections therein, and subsequently as a bed on which to establish such sections and for forming a permanent water tight and water proof chamber in which the sub- 30 aqueous tunnel lines may terminate and into which the road beds and tracks thereof may be continued and through which they may be established into communication with the subway lines and through communicating 35 systems of traffic. The foundation bed under such conditions is preferably reinforced in such a manner as to have a bridging capacity on any section line capable of supporting the maximum traffic passing there- 40 over and the reinforcing elements in such bed are preferably united in such a manner as to form a continuity of the tunnel bed of construction and other lines communicating with such water tight chamber. For the 45 primary uses of such chamber in the construction of a tunnel section, the foundation floor 105, see Fig. 2, is reinforced, ballasted and alined for the structural alinement and construction of the transportable tunnel sections to be built therein and transported 50 therefrom as self-floatable or as buoyable and transportable structures into position for placement through the water way end of such chamber, which is adapted to be opened and closed. Suitable means are provided 55 whereby such chambers may be filled with water for the purpose of floating the sections and suitable means are also provided for removing the water from such chambers 60 when the tunnel sections shall be moved

therefrom and the passageway closed, whereby the work of constructing the transporting tunnel sections can be carried on successively until the entire alined water bed shall be equipped therewith so that the last 70 placed tunnel section when building from one shore toward one of such chambers, will project into the passageway or to any desired extent therethrough. The water proof docks 20, see Fig. 2, are provided with an intermediate flooring 128 and a wharf flooring 101, the water proofing 119 of such structure forming a union between the floors and embedding the structural framework 125 of such construction and since this dock structure is described and broadly claimed in my co-pending application, filed December 7th, 1906, Serial No. 346,774, I have deemed it unnecessary to describe in detail the construction of this dock, since reference may be had to the above mentioned co-pending application for a detailed description thereof, it being deemed necessary in the present case to only show one manner in which the tunnel way and the subway lines can be 80 sealed into union with such a chamber. 85

It being now understood that the bed of construction is wholly or partially completed, the piers 85 being established and the bed of construction therebetween being ballasted to a desired grade, the next step in my novel method is the construction of the tunnel sections, which of course may be built either before, after or while the bed of construction is being completed. 95

The tunnel sections.—The first step in the construction of the tunnel section is the building of a structural framework 210, see Figs. 7, 8 and 12, which consists of upper and lower chords 22 and 23 united by vertical I-beams 24 and angle lattice work 25, the roof I-beams 27 and the floor I-beams which are secured together in any suitable manner, suitable metal or other bracket pieces 31 being employed which are secured to the vertical beams and the roof and flooring beams. End plates 39 are provided at the end of each tunnel section which are adapted to be secured together by means of the fastening devices 50, see Figs. 9 and 10, when two adjoining tunnel sections are lowered into alinement. A lining member 49 is employed which is composed of metal plates provided with suitable flanges, secured together by means of the fastening devices 51, 110 such lining member being riveted or otherwise secured to the vertical beams 24 by suitable fastening devices 52, as will be clearly understood by reference to Figs. 9 and 10. The outer face of the structural framework 115 is embedded in any desired kind of water proof material 57, such as for example asphalt, which is united with an outer sheathing element of metal or wood 58 and this outer sheathing element 58 is lined and 120

100

95

110

115

120

125

130

covered by a heavy protecting coating of any suitable water proofing material and since this material will be similar to the inner lining of water proofing, I have also indicated this by 57, see the upper right hand corner of Fig. 8 and the lower left hand corner of Fig. 8, as this water proofing at the ends of the structure is carried into union with the inner layer of such water proofing 57 and this water proofing is extended after the structures are laid to form a continuity of reinforced water proofing at the adjoining ends of meeting structures, as hereinafter more fully explained. The outer sheathing 58, see Fig. 8, when combined with the bridging framing construction 210 is adapted to operate as an outer framing or forming element for embedding the metal framing 210 in reinforcing material 56 such as concrete, cement or a combination of such materials. The continuous sheathing 58 and lining members 49, see Figs. 7, 8, 9 and 10, are structurally combined with chords 22, 23, 83 and 84, see also Fig. 12, and the tunnel way encompassing framing 210 and the decking and roofing and trussing elements, it being understood that such sheathing and lining members will be essential structural and reinforcing elements of the bridging tunnel unit sections and will operate in the sides of the structures as a trussed plate or apertured plate girders having upper and lower chords 22, 23, 83 and 84 with the flooring and roofing elements combined therewith, and effectually trussed against transverse stress and reinforced by the brackets 31. Such girders are embedded in reinforcing material 56 see Fig. 8 in which additional reinforcing metal elements 203 and 204 may be embedded in the upper and lower parts of the structure in the spaces confined by the knee brackets 31, see also Fig. 8, and otherwise on the inner face of the framing 210 so that any desired standards of reinforcement may be obtained against lateral as well as vertical strains. The bottom of the tunnel section is provided with controllable ballasting ports or tunnels 46 through which grouting, and if desired concrete and cement, can be passed to ballast the tunnel section when laid into union with the ballasted bed of the grade lining piers 85 or the ballasted bed 31. After the structural framework 210 has been suitably embedded in water proofing material and the outer framework 58 constructed, the tunnel sections are provided with water tight bulk heads 40 forming air locked chambers 66, said chambers being provided with ports or gates 89 through which the workmen may pass when the structures have been located in position and the outer union of adjoining structures completed. The tunnel sections are preferably not completed to the inner tunnel line 74, which indicates the inner face of the completed tunnel, see Fig. 12, until they are laid in position and located on the tunnel bed. The tunnel sections are provided at opposite ends with the inclined guides 44 and lugs 42, see Fig. 7, which are adapted to co-act with a corresponding structure at the meeting ends of adjoining tunnel sections. The tunnel sections are provided with adjusting devices 84, see Fig. 6, which provide for any defect or variation in the longitudinal adjustment of the tunnel sections as they are being laid into place, it being best seen in Figs. 6 and 7 that the tunnel sections are provided with the guide bars 12. The air locked chambers 66 are provided with air shafts 75, see Fig. 7, whereby when the tunnels are located on the foundation bed, access may be had to the air locked chambers from the platforms 7 or from suitable vessels 93 through such air shafts 75.

It being now understood that the tunnel section is partly completed and is provided at each end with the bulk heads 40, the next step in any novel method is the transporting of these tunnel sections into their proper position on the foundation bed.

Alignment of tunnel sections on the foundation bed.—The tunnel section is rendered floatable or transported by suitable vessels so that it passes between the side walls 3 and beneath the platforms 7 into proper location above the foundation bed so that the ends of the tunnel section will be above certain of the piers 85. In the present instance I have shown for the purpose of illustration, certain of the platforms or vessels 93 as provided with hoisting apparatus including cables 92 which support the tunnel sections. The tunnel section is now rendered sinkable in any desired manner and permitted to drop upon the foundation bed, the guide bars 12 co-acting with the guide members 41 of the piers 85 and if a tunnel section has already been laid, the lugs 42 co-act with the inclined members 44 carried by the adjoining tunnel section so that the tunnel section would interlock with a section already placed in position. As the tunnel section drops into place it will be accurately guided into position by the approximate aligning members 48 and the exact aligning members 47, it being understood that the ends of the tunnel sections will be located on the tunnel grade line 2.

The next step in the construction of the tunnel line is the formation of the lap joints between the meeting ends of two sections.

The lap joint construction.—It will be understood from the foregoing description that a chamber or channel is formed beneath the meeting ends of the sections of tunnel construction by the recess 297, see Figs. 7 and 11, in the upper surface of the foundation pier or aligning member 85, which communicates

with the chambers 54, see more particularly Figs. 11 and 12, on both sides of the tunnel structures and extending to preferably the top of the sections of tunnel construction when in position. These chambers are now 5 filled with ballast or grouting of any suitable material, such as for example concrete or cement, thereby completely embedding the metal reinforcements 209, which are located in or are part of the chambers 207 and 54.

In order to properly confine the ballast at the top of the tunnel structure, I employ a box or crib 208, see Fig. 8, which serves 10 to confine the ballast and this crib is formed with or has located therein metal reinforcements 209 so that after the joint formed by the meeting ends of two tunnel sections has been ballasted, the entire area around such 15 meeting ends will be completely sealed by an outer encompassing element of concrete, cement or a combination of such materials 68 suitably reinforced by metal elements embedded therein. A sealed joint will be 20 formed between the meeting ends of the tunnel sections by forcing ballast through the conduit 45, as will be understood by reference to Figs. 9 and 10, so that intermediate the end plates 39 of the adjoining tunnel 25 section a water tight seal of cement, concrete or other suitable material will be 30 formed, see Fig. 8. All the sections of the tunnel may thus be laid in position and the meeting ends sealed in the manner just described or any desired number of such sections 35 may be laid and the inner face of the tunnel line finished as the work of construction is carried on. The end plates 39 are secured together by means of suitable fastening devices, such as 50, see Figs. 9 and 10, and the chords 22, 23, 83 and 84 of the different 40 tunnel sections are united so that there will be a continuity of such chords extending from one end of the tunnel line to the 45 other end thereof. Entrance may be made through the ports 89 of the bulk heads 40 into the air locked chamber 66 at one end of the tunnel section or through the air shaft 75. If the ports 89 are opened through the 50 inner walls of the bulkhead the entire tunnel section will form an air locked chamber. The bulk heads between the meeting ends may be removed subsequently to the establishing of a water tight seal between the 55 ends and the reinforced and encompassing ballasted union. Such bulk heads can be removed with or without the employment of air locked chambers in the ends of the structure and with or without equipping the 60 structure with means for utilizing pneumatic pressure and controllable means whereby such air locked chambers or the tunnel chambers may be placed under pneumatic pressure. As seen most clearly in Fig. 8, 65 two bulkheads 40 are shown at the end of

a tunnel section which form the air-locked chamber 66 and each bulkhead is provided with a removable door 89. The air shaft 75 which is not shown in Fig. 8 opens into an air-locked chamber 66, as will be understood by reference to Fig. 7, in which such air shafts 75 are located directly above an air-locked chamber 66. The ends of the encompassing elements of the tunnel way are effectually sealed and reinforced by calking with a suitable filling and reinforcing material to make good any defect there may be in the ballast, which has been passed thereto in the process of ballasting the outer encompassing union of the meeting ends. 70

The water proofing and the elements of the bridging tunnel sections are reinforced with uniformity throughout and become a unit of structure with definite and reliable standards and adapted to operate in tunnel alignment with the bed of construction and the reinforced piers 85 as a traffic capacity structure, which is ballasted into union with the resistance bed of the water way between such piers 85, as will be now described. 80

The uniting of the tunnel sections with the foundation bed.—As hereinbefore described, the tunnel sections are provided in their bottom with controllable ballasting ports 46. After the tunnel sections are located in position, piles may be established through these ballasting ports into the foundation bed in order to reinforce such bed to any desired standard of resistance. The foundation bed is preferably built up to 100 such a height that after the tunnel sections are located in position but slight ballasting will be necessary to ballast such sections into union with the resistance bed 15 or 16, depending upon the grade to which the tunnel 105 section has been previously constructed. Grouting, together with concrete, cement or other suitable filling material is now forced through the ballasting ports 46 to establish a continuity of ballasted union between the 110 foundation bed of construction with the several tunnel sections throughout the length of such tunnel line construction. As soon as the concrete, cement and other filling, if desired, has become set, the side pilings or 115 walls 5 are cut off at a suitable distance above the top of the tunnel and the tunnel line is completely embedded with a layer of any desired thickness of concrete, cement or other filling 100 and 120 the whole structure so formed is completely covered with suitable filling material, as will be best understood by Figs. 7, 11 and 12. The ends of the tunnel are extended into the shore in water proof union 125 with the subway or surface traffic lines or the connections thereto, as hereinbefore described or are formed in water tight union with the water proof chamber of pier or dock structures or otherwise with shore ap- 130

proaches or subways. Under such conditions the trussed bridging structures will reinforce the foundation bed to a continuity of bridging capacity on any section line in excess of the bridging capacity of the tunnel sections when ballasted into union therewith, and in the event of any break or defect in the foundation bed, the novel manner in which the unit sections of structure are constructed and united and established in reinforced and reinforcing union with the bed will safeguard against any break or defect therein, and against any undue or excessive strain being imposed on the construction or bed.

In the actual establishing of the tunnel structures on their foundation bed in accordance with my novel method, I may first establish a tunnel section in alinement on the graded and alined water bed between the ends of the tunnel line and build therefrom to both shores or I may transport the different sections as built into position over the alined water bed, lower such sections into position in accurate alinement on such bed so as to build from both ends of the first placed sections toward the shore successively into water tight union with the shore connections, which may be through the water proof chambers of the wharf structures having their water ends extending to the port warden lines or otherwise, and with such walls extending back to the street lines and otherwise into the shore to any desired extent, with passageways to subways if desired. I may also establish a section on one shore in water tight union with the shore connection, which may be the water tight chamber of a wharf or other construction, whereby a water passageway will be established to the bulk head at the end of each section, and such transportable structure, when in position, may be placed in alinement on such graded and alined water bed so that the end next the section first placed will be in close proximity thereto on the graded bed.

In order to construct with greater rapidity and economy and with great accuracy the reinforced portions 2 and the channel 207 and side alining resistances 17-17, 18-18 and the chamber 54 with reinforcing 209 or otherwise in the framing, I may construct such in the dry docks or in any other suitable place so as to form a transportable unit which may be conveyed by means of suitable floats or vessels, and then sunk into position in proper alinement between the side pilings 5-5 or continuous lines of side pilings or walls and ballasted into union with the bed in accurate grade, side and sectional alinement in order to co-act with the tunnel sections as lowered into position to bring the same into proper alinement.

In the drawings I have shown the piers

85 established at uniform distances apart throughout the tunnel line and pilings capped with ballast and side walls of pilings as reinforcements in the foundation bed and such are designed to be employed where there is any uncertainty in the bed and if desired continuously throughout the tunnel line as a further reinforcement to the unit area of resistance bed, but it will be the exception where piers will be needed otherwise than for alinement purposes, since a properly excavated and ballasted area bed will afford, when reinforced by the bridging tunnel unit sections united together, ample resistance and capacity. It is sometimes 80 advisable and practicable under my novel method, to bridge the tunnel ways across any channels in the water bed or establish the structure partly above or near the surface of the ordinary bed to avoid heavy 85 grades.

I have shown and described the sections and means by which subaqueous tunnels can be established with reliable standards of capacity in construction and by which every element in construction can be established as units or unit series and as single and multiple tunnel ways with absolute continuity of such construction from shore to shore or into union with my novel construction of wharves, but I do not confine myself to the exact construction or plans of procedure since my invention in its broad scope is not limited to the manner herein shown, which simply shows one form of a construction wherein my novel method may be carried out.

It will now be apparent that the road beds of the passages through the chambers of the docks or wharves with a continuity of unit bridging capacity of either single or multiple tunnel construction is established with reliable standards on all section and longitudinal lines throughout the foundation area of construction so as to provide adequate factors of safety for the maximum train loads which can possibly be imposed upon any such unit or unit areas in single or multiple construction in continuity throughout the tunnel line. A bridging 105 construction of area bed reinforcement can be built in coffer-dam or dry dock chambers and transported by suitable detachable and floatable vessels into position and alinement along a suitable graded, ballasted and alined bed and be ballasted into union therewith. If the supporting vessels shall be detachable from such reinforced bed, the latter material may then be equipped with the tunnel way construction which can be accurately alined along such bed, as hereinbefore described.

It will now be understood by those skilled in this art that each tunnel section consists of one or any desired number of units 130

of single or multiple bridging tunnel way construction so that on any section line, either sectional or longitudinal, the tunnel section itself, as well as the foundation bed 5 of construction to which it is united, will each have a bridging capacity capable of supporting the maximum train loads so that in case there should be a defect in the foundation bed of construction the bridging capacity 10 in the tunnel structure will be sufficient to prevent any break down of the reinforced water proof construction of the tunnel way, consisting of the transportable sections.

15 Having thus described my invention, what I claim as new and desire to secure by Letters Patent, is:—

1. The method of constructing subaqueous tunnels which consists in establishing 20 a working chart above the water bed, excavating a channel in such bed to the grade and dimension alinement, establishing an alineable grade, equipping such bed with grade and side alining supports and alining 25 platforms, constructing transportable structures having bridging capacity in each unit length thereof, floating such structures beneath said platforms, lowering such structures into tunnel way alinement, establishing 30 bridging capacity water tight unions at the meeting ends of the structures, and ballasting the united structures into union with the bed and its equipments.
2. The method of constructing tunnels 35 which consists in establishing a working chart above the water bed, excavating a channel in the water bed in accordance with such chart, piling the excavated bed, capping such piles with ballast, equipping the 40 channel with means for alining the tunnel structures while being placed, constructing transportable tunnel structures having bridging capacity in each unit length thereof, locating such structures in water tight 45 bridging capacity union in exact tunnel way alinement along such ballasted bed, and ballasting the united structures into union with the ballasted bed and its equipments and embedding such united structures with ballast. 50
3. The method of constructing tunnels, which consists in constructing in or extending from the shore subwater line water proof chambers having passages there- 55 through in tunnel alinement, establishing structural resistance beds in such chambers, constructing thereon transportable tunnel sections, grading and alining the water bed, transporting the structures from said cham- 60 bers into tunnel alinement, lowering the structures to placement into exact alinement on the graded and alined bed, joining the ends of meeting structures in water tight union until the last placed structures ex- 65 tend into the passageways of the water tight

chambers, and then uniting the last placed structures into water proof union with such chambers.

4. The method of constructing tunnels, which consists in constructing in or extending from the shore subwater line water proof chambers having passages there- 70 through in tunnel alinement, establishing structural resistance beds in such chambers, constructing thereon transportable tunnel sections, grading and alining the water bed, transporting the structures from said chambers into tunnel alinement, lowering the structures to placement into exact alinement on the graded and alined bed, joining the ends of meeting structures in water tight 75 union until the last placed structures extend into the passageways of the water chambers, uniting the same into water proof union with such chambers, and then ballasting the structures into union with the bed thereunder.

5. The method of constructing subaqueous tunnels, which consists in constructing in or extending from the shore subwater line 90 water proof chambers having passages therefrom in tunnel alinement and adapted to be opened and closed, establishing structural and alineable resistance beds in such chambers, constructing thereon transportable structures consisting of any desired 95 number of units, grading and alining the water bed and equipping the same with approximate and exact side alining piers, transporting the structures through said 100 passages into tunnel alinement between the side alining piers, lowering the structures into exact alinement on the graded and alined bed, joining the ends of meeting structures in water tight union, and uniting the end structures into water tight union 105 with such chambers.

6. The method of constructing tunnels, which consists in constructing in or extending from the shore subwater line water 110 proof chambers having passages therefrom in tunnel alinement, grading and alining and equipping the water bed with bridging and grade alining piers, constructing trans- 115 portable structures having bridging capacity in each unit length thereof, transporting the structures into tunnel alinement, establishing the structures in exact alinement on the grade so that the ends of meeting structures are located in the side alining piers, 120 uniting the meeting ends of adjoining structures with inner and outer lap joint reinforcements to form a continuity of structural, bridging, water proofing, and re- 125 inforcing elements, and joining the end structures in water proof union with said water proof chambers.

7. The method of constructing subaqueous tunnels which consists in constructing in or extending from the shore subwater line 130

- water proof chambers having passages therefrom in tunnel alinement adapted to be opened and closed, establishing a structural foundation bed in such chambers, constructing thereon transportable tunnel sections, grading and alining the water bed and equipping the same with piers, transporting said structures through said passages and establishing them in tunnel alinement on the graded and alined water bed, uniting the ends of adjoining structures to form a continuity throughout the tunnel of bridging, structural, water proofing and reinforcing elements, joining the end sections in water proof union with such chambers, and ballasting the united sections into union with the resistance bed and its equipments. 70
8. The method of constructing subaqueous tunnels, which consists in establishing alining platforms above the water bed with a visible record of the work to be done, grading and alining the water bed, reinforcing the same to definite standards of resistance and equipping the bed with means for the approximate, automatic and exact alinement of the tunnel structures when placed, constructing transportable structures and establishing them with a reinforced lap joint union in tunnel alinement on the graded and reinforced bed, and then ballasting the structures into union with such bed and its equipments. 80
9. The method of constructing subaqueous tunnels, which consists in alining the bed, equipping the alined bed with a water tight chamber having a reinforced water tight floor alineable and serviceable as a structural, alining and construction bed for transportable tunnel structures during construction, locating a tunnel structure on such bed, and uniting it in water proof union with the tunnel construction extending into such chamber. 90
10. The method of constructing subaqueous tunnels, which consists in alining the water bed, constructing a water tight chamber having a passage therefrom in tunnel alinement and adapted to be opened and closed, establishing a structural reinforced bed in tunnel alinement with such water tight chamber, constructing in such chamber transportable tunnel structures, and transporting the sections therefrom through said passageways. 100
11. The method of constructing tunnels, which consists in establishing a working chart above the water bed, equipping the bed with side pilings or walls, providing means between the side walls at predetermined places to form a water tight chamber, grading, alining and reinforcing the bed of the chamber for the alinement and construction of transportable tunnel structures, constructing such structures in such chamber, transporting the structures from such chamber and locating them in water tight union between the side pilings or walls, ballasting the united structures into union with the bed and side walls, and covering such united structures with ballast. 110
12. The method of constructing subaqueous tunnels, which consists in grading and alining the water bed, equipping the bed with side pilings or walls, excavating and equipping the bed with chambered side alining elements, providing means between the side walls to form a water tight chamber, constructing tunnel structures in such chamber, transporting the structures from said chamber through a passageway adapted to be opened and closed and establishing the structures in water tight union on the graded and alined water bed between the side pilings or walls with their meeting ends between the chambered side alining elements, ballasting the meeting ends to form a lap joint union, and then ballasting the united structures into union with the graded bed. 120
13. The method of constructing subaqueous tunnels, which consists in grading the water bed and shore terminals, equipping such bed with side walls of any desired length, providing removable closures therebetween at one or more bridging tunnel unit lengths to form a water tight chamber, grading and alining the bed of such chamber, establishing on such chamber bed a tunnel section consisting of a desired number of unit lengths, each of said lengths having bridging capacity therein, and ballasting the section into union with the bed and its equipments. 130
14. The method of constructing subaqueous tunnels, which consists in establishing a working chart above the water bed, excavating, grading and alining such bed, equipping such bed with side walls of any desired length, providing removable closures between such walls at one or more bridging tunnel unit lengths to form a water tight chamber, excavating the bed within such chamber, grading, reinforcing and alining such chamber bed, constructing in such chamber transportable structures having bridging capacity in each unit length thereof, removing one of said closures, conveying the structures therethrough and establishing the same along a graded and alined bed in tunnel alinement with such chambers, building other sections and conveying such therefrom in a similar manner and into alinement to unite with the last placed section having the meeting ends of the sections in reinforced bridging capacity, and water tight union until the shore connections are reached and joining the end sections in water tight union with the shore connections. 140
15. The method of constructing subaqueous tunnels which consists in grading and alining the water bed, equipping the same with 150

- water proof drainage wells, establishing on such bed a tunnel construction having bridging capacity in each unit length thereof, ballasting the tunnel construction into union with its bed, uniting the drainage wells in water proof union with the tunnel way, and providing means of drainage thereto for removing the water therefrom.
16. The method of constructing tunnels, which consists in grading and alining the water bed, equipping the same with piers at desired points, establishing a water proof drainage well in one or more of said piers, establishing on said bed a subaqueous tunnel having bridging capacity in each unit length thereof, uniting the enveloping walls of the drainage wells in water tight union with the tunnel way, and providing means for removing liquid from said wells.
17. The method of constructing tunnels, which consists in establishing a working chart above the water bed, excavating, grading and alining such bed, equipping the bed at one or more points with a subwater line water proof chamber having a passageway adapted to be opened and closed, constructing transportable tunnel structures, locating the same on the graded and alined water bed so that the ends extend into the passageways of the chambers, and forming a water-tight union between the end of the sections and the passageways to establish such chamber as an equipment or part of the subaqueous tunnel.
18. The method of constructing subaqueous tunnels, which consists in constructing trussed bridge framings and embedding the same in concrete to form tunnel sections having bridging capacity in each unit length thereof and provided with water tight removable ends floating the sections into position over a suitable graded and alined water bed, successively establishing such transportable structures in tunnel way alinement, sealing and uniting the meeting ends from both ends of such first placed structures successively to the shore connections, providing the shore connections with sub-water line chambers, uniting the adjacent structures into water tight union therewith, and then removing the water tight ends and establishing the tracks through the unit sections.
19. The method of constructing subaqueous tunnels, which consists in constructing tunnel sections having multiple tunnel ways, each tunnel way section being encompassed by elements of construction in which there is continuity of water proofing, embedding and reinforcing material, the ends of such sections being closed by removable means, grading and ballasting the water bed to a desired resistance grade, establishing the sections successively in co-alinement on such bed, sealing and uniting the meeting ends and the shore ends into water tight union, 65 removing the removable means at the ends of each section, building up a continuity of inner water proofing, embedding and reinforcing material at the meeting ends of the sections, and ballasting the sections into 70 union with the graded and ballasted bed.
20. The method of constructing subaqueous tunnels, which consists in suitably grading and alining the bed of a waterway, reinforcing such bed with ballast and with 75 reinforced supports at tunnel unit distances apart, constructing tunnel sections having a water proof, reinforced bridging construction in each tunnel unit length, locating the sections with the ends of unit lengths on said 80 supports, uniting the ends of tunnel sections, and ballasting the sections into union with the equipped bed.
21. The method of constructing subaqueous tunnel lines which consists in equipping 85 the water bed with pilings extending to a suitable height above the water level along approximate side alining lines of the bed of construction, and equipping such pilings with working and alining platforms at a 90 suitable height above the water level across the bed of construction on defined section and construction lines along the length thereof and projecting on such platform system and its adjunets, the longitudinal center 95 and side lines of tunnel way construction and lines for the equipment of the water bed with approximate and exact side and sectional alining supports.
22. The method of constructing subaqueous tunnels which consists in primarily establishing above the water level and bed of determined tunnel way construction and across the same, visible lines of survey and construction corresponding to the plans of 105 survey and construction on corresponding sections thereof.
23. The method of constructing subaqueous tunnels which consists in employing suitable means to support and maintain and in 110 establishing on such means, visible lines of alinement and tunnel way construction above the water level at a series of places along and across the water way and the determined bed of tunnel way construction in 115 conformity with the prepared plans of survey and construction.
24. The method of constructing subwater line passages across water ways and into opposite shores which consists in constructing the same in alinement and union with a suitable passageway construction extending lengthwise through the subwater line parts of a wharf structure extending into the water way and then completing the tunnel 125 to the opposite shore.
25. The method of constructing subaqueous tunnels, which consists of grading a

- water bed, reinforcing such bed with equipment to secure definite standards of support, equipping said bed with means for automatically alining tunnel sections during placement, constructing transportable tunnel sections, locating such sections in tunnel alinement on the equipped bed, uniting the meeting ends of tunnel sections, and ballasting the tunnel way thus formed into union with the reinforced bed. 5
26. The method of constructing subaqueous tunnels, which consists in grading the water bed, establishing at defined distances apart piers, ballasting the bed between such 10 piers, constructing transportable water proof tunnel sections having bridging capacity in each unit length, locating the sections in alinement on such piers, ballasting the ends of meeting sections to form a water tight union at such points, and then ballasting the sections into union with the piers and the bed thereunder throughout the entire length of the tunnel line. 15
27. The method of constructing subaqueous tunnels, which consists in establishing a working chart above the water bed, excavating and grading such bed and equipping the bed at one or more points with a water proof subwater line construction and tunnel way equipment chamber having a passageway adapted to be opened and closed, building in such chamber transportable tunnel structures, removing such structures and locating them in alinement along the graded and equipped bed, uniting the ends of meeting structures, and closing the ends of the passageway from the chamber by uniting therewith the ends of tunnel sections. 20
28. The method of constructing subaqueous tunnels, which consists in grading and alining a water bed, constructing trussed bridge framings, embedding them in concrete and closing the ends to form transportable tunnel sections, floating such sections into position over the equipped bed, lowering the sections into alinement and successively establishing the sections in tunnel way alinement, sealing and uniting the meeting ends from both ends of the first placed sections successively to the shore connections and into water tight union therewith, and ballasting the tunnel structure formed by the sections into union with the bed. 25
29. The method of constructing subaqueous tunnels, which consists in constructing tunnel sections having a bridging construction in each unit length thereof and provided with a continuity of water proofing, embedding and reinforcing material, the ends of the sections being closed by removable ends, grading and resistance alining the water bed, locating the sections successively in co-alinement on such bed, sealing and uniting the meeting ends by a water tight lap joint union and uniting the shore ends into water tight union with the shore connections, removing the ends of tunnel sections, building up a continuity of the inner bridging construction, water proofing and reinforcing material at the ends of meeting sections, and ballasting the united sections into union with the bed and its equipments. 30
30. The method of constructing subaqueous tunnels, which consists in encompassing the shore end of a water bed with a piling or wall extending along the shore and back therefrom beyond the dimension alining so lines of a tunnel construction to be established and along both sides of the area water bed to a defined line, excavating the area so inclosed to a grade below the grade of the tunnel, reinforcing such bed and establishing the requisite standards of capacity therein, grading, ballasting and water proofing such bed to form a water proof foundation floor over the entire area, providing the foundation floor at the water end with piers for supporting and alining a tunnel section when lowered, building in the chamber thus formed a tunnel section, admitting water into such chamber, floating the tunnel sections from such chamber into tunnel alinement, joining the ends of tunnel sections and uniting the sections into water proof union with such chambers, and then ballasting the sections into union with the foundation bed thereunder. 35
31. The method of constructing tunnels, which consists in establishing along the water bed at unit distances apart piers for supporting the tunnel construction, building up in these piers drainage wells, building a tunnel construction having a bridge framing in each unit length thereof so that the ends of unit lengths are supported on the piers, providing the tunnel with drainage channels, uniting these channels in water proof union with the drainage wells and filling the space between the piers with ballast to unite the tunnel construction with the foundation bed thereunder. 40
32. The method of constructing tunnels, which consists in building transportable sections, consisting of a bridge framing embedded in concrete and water proofing material, said framing being provided with chords also embedded in concrete and water proofing material, lining the inner face of the tunnel with heat resistant material, locating the sections in tunnel alinement on a suitable equipped bed, uniting the ends of meeting sections and forming a continuity of bridge framing chords and water proofing material, and ballasting the united sections into union with the foundation bed. 45

33. The method of constructing tunnels which consists of constructing shore connections with subwater line waterproof chambers, and uniting the ends of a tunnel line in waterproof union with said chambers.

34. The method of constructing tunnels which consists of constructing shore connections with subwater line waterproof cham-

bers, uniting the ends of a tunnel line in waterproof union with said chambers, and 10 uniting a subway line in waterproof union with one of said subwater line chambers.
